BREAKER BLOCK FOR ROLLING MILLS

William Heap Bailey, London, England, assignor
to The British Iron and Steel Research Association, London, England, a British company

Application October 28, 1949; Serial No. 124,184
In Great Britain October 28, 1948

6 Claims. (Cl. 80—57)

1

This invention relates to a breaker block to be used for the purpose of limiting to a safe figure the load which can be applied to parts of machines. In particular, the breaker block of the invention may be used in a rolling mill for the purpose of limiting the load which can be applied to the roll neck, but it may also be employed for an analogous purpose in other machines, for example, in power operated shears.

In most rolling mills the form of breaker block at present used consists of a round or square cast iron block which is placed on top of the chock and receives the end of the screw-down gear screw in the middle of its upper face. The underside of the block is recessed, so that it bears on the chock at its periphery or at its ends only. When a sufficient overload occurs, the block fractures and allows the chock to rise. The load at which this will happen is, however, uncertain owing to the inconsistency of the mechanical properties of the material of which the breaker block is composed. The present invention provides a breaker block so designed that the breaking load can be predetermined within close limits.

According to the present invention a breaker block comprises a body member having a chamber therein and a load receiving member bearing against the outer face of a diaphragm secured over the chamber and means for maintaining fluid under pressure in said chamber whereby a load applied between the load receiving member and the rolling mill chock is limited to the sum of the fluid load on the inner face of the diaphragm and the load required to shear the diaphragm.

The accompanying drawings illustrate, by way of example, a breaker block for a rolling mill. In these drawings:

Figure 1 is a sectional side elevation of a rolling mill showing the breaker block in its working position, and

Figure 2 is a perspective diametrical section through the breaker block.

In the particular construction shown in the drawings the base of the breaker block is formed by a circular body 1, 7 inches in diameter and 1 3/4 inches thick adapted to rest upon the chock 11 of a rolling mill. The upper face of the body is recessed to form a circular chamber 2. The upper part of this chamber 2 is surrounded by a short upstanding spigot 3 having at its upper end a sharp inwardly projecting lip 3a which forms the actual mouth of the chamber. This spigot is hardened and ground. A diaphragm 4, of soft copper, 0.005 inch thick, is laid over the

mouth of the chamber and clamped between the upper face of the body and the underside of a second body member in the form of an annular steel disc 5, which second body member mates with the body 1 and is secured to it by bolts 6. A soft copper ring 7, surrounding the spigot 3, provides a seal to ensure that the chamber 2 is fluid tight. The bore of the annular disc 5 is tapered upwardly from a diameter of 3 1/2 inches at the bottom to a diameter of 2 1/2 inches at the top. This bore is filled by a frusto-conical steel disc 8, one inch thick, whose lower surface is accurately flush with that of the annular disc 5. The lower face of the conical disc 8 is hardened and ground, the periphery of this face being relieved to form a sharp lip 8a, which is a close fit with the lip 3a on the spigot, so that these two hardened and ground lips form in effect a punch and die.

The chamber 2 communicates with the lower face of the body 1 through an inlet passage 9 provided with a non-return valve 10. Through this passage fluid is injected into the chamber 2 so as to compress the air already in the chamber to a pressure which will support the difference between the load at which the breaker is intended to operate and the load required to shear the diaphragm 4. The device is installed in the mill with the underside of the body resting on the top of the chock 11 and the end of the screw 12 of the screw-down gear bearing on the upper surface of a spherically seated pad 13. The underside of the frusto-conical disc 8 rests upon the diaphragm 4, so that the load which can be applied to the chock 11 is limited to the fluid load on the underside of the diaphragm plus the load required to shear the diaphragm. Any excess of this fluid thrust over the roll force is carried by the annular disc 5. It will be seen that if the thrust from the screw 12 should exceed the fluid thrust by more than the shearing force of the diaphragm 4, shearing will take place. This will enable the fluid to pass into the clearance space 14 between the frusto-conical disc 8 and the annular ring 5 and also into the space which will have opened between the conical surfaces of the disc 8 and of the ring 5 as the former descends relative to the latter. The chock 11 will now be free to rise and relieve the force on the mill. The diaphragm 4 is not intended to contribute to the load carrying capacity but only to prevent the escape of fluid until operation of the breaker takes place.

In two tests with this apparatus fitted to an ordinary compression testing machine the cham-

ber 2 was filled with nitrogen gas from a containing cylinder. The breaker block operated at total loads of 6.4 and 6.3 tons. The pressure of the nitrogen in the chamber was the same in both cases. A third test was carried out to determine the load required to shear the diaphragm with the chamber filled with air at ambient temperature and pressure. The load in this test was 0.95 ton.

If a liquid is employed any convenient means and procedure may be employed for the injection of the liquid into the chamber 2 to produce the required pressure. One method of effecting this operation is to place the assembled breaker upside down in a compression testing machine. An open-topped cylinder is screwed into the inlet passage 9 in the body 1 and filled with the liquid. A piston is inserted in the cylinder and forced down with the straining motion of the testing machine until the load indicated reaches a figure calculated from the area of the piston and the pressure required. The piston and cylinder are then removed and the inlet passage closed by a plug 10 to prevent the entry of dirt. Preferably a plain piston is used, fitting the cylinder sufficiently closely to make packing unnecessary. However, the piston may be provided with a loose head having a stem fitting into a bore in the body of the piston, thus allowing a soft rubber packing to be interposed between the body and head and compressed by the differential pressure due to the "unsupported area" of the cross section of the stem.

Having now particularly described and ascertained the nature of my said invention and in what manner the same is to be performed, I declare that what I claim is:

1. A breaker block comprising a body member having a chamber therein, a diaphragm extending over the chamber, means including an annular member secured to said body member to clamp said diaphragm to said body member to provide a hermetic seal for said chamber, a load receiving member within the bore of said annular member and seated upon said diaphragm, the diaphragm having a shear resistance equal only to a minor fraction of the load to be carried by said load receiving member, said body member being provided with an opening for the introduction of a pressure fluid into said chamber, and means for closing said opening to prevent the escape of the pressure fluid from said chamber, whereby the load which can be applied between the load receiving member and the body member is limited to the sum of the fluid load on the inner face of the diaphragm and the load required to shear the diaphragm.

2. A breaker block according to claim 1, wherein in the peripheral edge of the load receiving member and the adjacent edge of said body member at the opposite side of said diaphragm are formed with co-operating lips for shearing the diaphragm when the load receiving member moves inwards.

3. A breaker block as recited in claim 1, wherein in said load bearing member has a spherical surface at the face thereof opposite said diaphragm, in combination with a pad member having a complementary spherical surface in engagement with the spherical surface of the load bearing member.

4. A breaker block according to claim 1, wherein in said annular member and said load receiving member have cooperating stop surfaces preventing movement of said load bearing member with respect to said annular member by pressure exerted upon said diaphragm by a pressure fluid within said chamber.

5. A breaker block as recited in claim 4, wherein in the annular member has a bore including an inwardly flaring conical wall surface, and said load bearing member has a complementary conical wall surface seated against the conical wall section of the annular member; said complementary wall surfaces constituting said stop surfaces.

6. A breaker block as recited in claim 5, wherein in the bore of said annular member has a cylindrical wall section between said conical wall surface and the face thereof engaging said diaphragm, said load bearing member has a cylindrical wall section opposed to and of less diameter than the cylindrical wall section of said annular member, and said load bearing member has a cutting lip projecting outwardly from the cylindrical wall surface thereof, whereby shearing of said diaphragm opens communication between said chamber and the interspace between the respective cylindrical wall sections of said annular member and said load bearing member.
